Primary Examiner—Louis S. Zarfas*Assistant Examiner*—Monica A. Weingart*Attorney, Agent, or Firm*—Haynes and Boone, L.L.P.;
Brandi W. Sarfatis[57] **CLAIM**

The ornamental design for a waist trimmer, as shown and described.

DESCRIPTION

FIG. 1 is a front perspective view of the waist trimmer showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a right side elevational view thereof; and,

FIG. 7 is a left side elevational view thereof.

The broken line showing of a man's body in FIG. 1 is for illustrative purposes only and forms no part of the claimed design.
